UNITED STATES PATENT OFFICE.

ALEXANDER DOW, OF NEW YORK, N. Y., ASSIGNOR TO MERGENTHALER LINOTYPE COMPANY,
A CORPORATION OF NEW YORK.

LINOTYPE-MACHINE.

No. 886,584.

Specification of Letters Patent.

Patented May 5, 1908.

Application filed June 28, 1907. Serial No. 381,275.

To all whom it may concern:

Be it known that I, ALEXANDER Dow, of New York city, county of New York, and State of New York, have invented a new and 5 useful Improvement in Linotype-Machines, of which the following is a specification.

This invention has reference more particularly to linotype machines wherein slugs or linotypes, each bearing the type to print an entire line, are cast in a mold against a composed line of matrices and intermediate spacers, the latter adapted to expand or justify the line to the predetermined length after it has been composed.

15 My invention relates to expandible spacers of improved form, in combination with co-operating matrices and means for assembling the matrices and spacers in line.

Each spacer consists of two unconnected 20 oppositely tapered wedges adapted to be separately inserted in the line between the matrices, and thereafter moved one past the other to expand or increase the length of the line.

25 My assembling mechanism includes devices whereby one of the wedges in its course to the line is caused to release the companion wedge and effect its delivery to the line, whereby the proper delivery of the wedges in pairs is assured.

30 My improved matrices consist each of a flat metal plate having the letter or matrix proper in one of the vertical edges, this edge being provided with horizontal shoulders at 35 the upper and lower ends, while the opposite or rear edge is practically continuous or without such shoulders.

While I have represented details of construction which are found to operate in a 40 satisfactory manner, it is to be understood that the parts may be modified in form and arrangement at will, provided only one of the spacing members is utilized to deliver or control the delivery of its companion to the line, 45 this action being wholly and broadly new in the art.

The expandible spacers and the matrices 50 are not in themselves claimed as a part of the present invention, being made the subject of independent applications for Letters Patent.

Referring to the accompanying drawings,—Figure 1 is a front elevation of my improved composing mechanism. Fig. 2 is an end view of the same looking from the left. 55 Fig. 3 is an end view looking from the right,

portions being shown in vertical section. Figs. 4 and 5 are front elevations illustrating the manner in which the advancing wedge actuates the mechanism for releasing its companion. Fig. 6 is a front elevation, showing 60 on a larger scale the means for releasing the long wedges or spacing members. Fig. 7 is a vertical section on the line 7—7, Fig. 1, showing the manner in which the long spacing members are deflected laterally in their passage to the line. Fig. 8 is a front elevation of the lower part of the assembling mechanism on an enlarged scale. Fig. 9 is a horizontal section of the same on the line 9—9, Fig. 8, looking in a downward direction. Fig. 10 is 70 a top plan view of the star-wheel and adjacent assembling devices. Fig. 11 is a detail view of the connections for driving the star-wheel. Fig. 12 is a horizontal section through the center of the star-wheel and adjacent 75 parts. Fig. 13 is a vertical section illustrating details of the spacer magazine. Fig. 14 is a cross-section on the line 14—14 of Fig. 9. Fig. 15 is a front elevation of the star-wheel and adjacent parts. Fig. 16 is a cross-section 80 through the assembler, showing the manner in which the matrices and spacing members are sustained in their first positions. Fig. 17 is a front elevation of the same, the forward support being removed. Figs. 18 85 and 19 are views corresponding to Figs. 8 and 9, but with the spacers expanded to justify the line. Figs. 20 and 21 are respectively a top plan view and a side view of one of the shorter spacing members. Figs. 22 and 23 90 are side elevations of a matrix as seen from opposite sides. Fig. 24 is an edge view of the same.

Expandible spacers or justifiers.—My improved spacers A, with which the assembling 95 mechanism is designed to coöperate, are illustrated in detail in Figs. 16 to 21, and consist each of two members a, a'. The shorter members a are designed to be seated and locked in the composed lines of matrices. They consist 100 each of a thin flat plate of essentially the same size and marginal form as the matrices hereinafter described. Each of these spacer members a is formed on one edge with the projecting shoulders a² and a³ at the upper 105 and lower ends respectively, for the purpose of sustaining them in the composed line and preventing their vertical movement therein, as hereinafter described. The opposite or rear edge is continuous or without the shoul- 110

ders, but is provided near the upper end with a notch or indentation a^4 .

The members a are of a width greater than the coöperating wedges a' , and are recessed longitudinally in one side face to receive the other members, the recess being made of increasing depth from the upper to the lower end, so that this recessed portion is in vertical section of a wedge form.

- 10 The member a' , of much greater length than its companion, is made of increasing thickness from its upper to its lower end, or in other words, it is a long wedge of suitable width to fit into the recessed side of the short member a . The taper or inclination of the wedge corresponds with that of the recessed portion of the member a , so that when the two are united, their outer surfaces will be parallel.
- 20 The member a' is adapted to slide longitudinally along its companion, and the two members constitute jointly an expansible space, or in other words, a space which may be expanded or increased in thickness as to the portion in the line, by sliding the long member through the line.
- 30 The member a' has its upper end provided with laterally projecting ears a^5 by which to sustain it in its magazine and during its travel through the machine, as hereinafter explained.

The upper end of the member a' , which stands always above the member a , is also preferably made of a thickness greater than the portion immediately below, or in other words, of a thickness greater than the upper end of the tapered portion, and this for the purpose of giving it the necessary strength and affording sufficient surface for the certain action of the devices which release it from its magazine.

It will be observed that the recessing of the side face of the part a leaves vertical edges or shoulders along the sides of the recess, and that these shoulders serve to retain and guide the edges of the member a' and to hold the vertical edges of the two parts flush at the front side. This is important inasmuch as it enables these faces to be presented tightly against the mold between the adjacent matrices, so that the leakage of molten metal is prevented.

Matrices.—The matrices B consist each of a flat plate having one vertical edge recessed to form the shoulders b and b' at the upper and lower ends, and with the character or matrix proper b^2 formed in said edge between the shoulders. The rear vertical edge of the matrix may be continuous or without shoulders, but is preferably provided with a small notch b^3 , the upper side of which is on a level with the shoulders b . The upper end of the matrix may be notched and provided with distributing teeth b^4 , as shown, similar to those used in the matrices of the well known

Mergenthaler linotype machine, or the matrix may be provided with any other appropriate features for effecting their proper distribution. The distributing feature of the matrix is foreign to the present invention, and may be modified at will. It will be observed that these matrices have essentially the same contour as the short justifier members a , and that they are of similar dimensions. When, therefore, the spacers are seated between the matrices in a composed line, as shown in Figs. 16 and 17, the matrices and the spacer members a will both project in front and in rear of the long spacer members a' . This admits of the matrices and members a being sustained upon and between the lower flanges of two parallel horizontal supports or rails C and C', while at the same time the intermediate members a' will be independently supported by the ears at their upper ends on the upper flanges of the same guides. It will be perceived that under this arrangement the short members or wedges a are held in place properly between the matrices and in line therewith, while the members a' are left free to pass upward through the line, as shown in Figs. 18 and 19, whereby the line of less than the required length may be expanded or justified to the predetermined length against the jaws or abutments D or other supports of suitable character.

When the composed line of matrices and spacers is presented in front of the mold, as usual in this class of machines, and as indicated in Fig. 18, the front of the mold may engage over the lower shoulders of the matrices and the short spacer members a to hold them in proper alinement. The support or pressure device M, acting against the rear edges of the matrices and members a , will support their forward edges tightly against the mold, and the longitudinal shoulders on the members a will at the same time hold the members a' , which are not acted upon by the support M, forward against the mold.

Assembling mechanism.—Passing now to the assembling mechanism, attention is directed to Figs. 1 to 15.

E represents an upright raceway having a series of channels through which the matrices are successively delivered in the order of their selection from a magazine or holder, which will be provided with releasing devices connected with finger-keys, all of which parts are foreign to the present invention. As suitable mechanisms for this purpose are familiar to all persons skilled in the art, it is unnecessary to describe them herein.

F represents an inclined belt upon which the matrices are received, and by which they are delivered one after another into the assembling space in front of a star-wheel G, and thence between the horizontal guides or rails C, C', before referred to.

The short members a of the spacers or jus-

ifiers will be stored in the magazines in the same manner as the matrices, and will be delivered therefrom by a finger-key mechanism in like manner. They descend through the left-hand channel e' of the raceway E in front of the star-wheel, and are delivered to the line in the same manner as the matrices. As each of these shorter wedges enters the line, it is necessary that it should be accompanied or speedily followed by the companion wedge a' , so that the two may enter the line together in advance of the following matrix. To this end, I utilize the descending member a for releasing its companion a' in the manner following.

The long members or wedges a' are suspended in a magazine H , having inclined top rails h , whereon the ears at the upper ends of the wedges are sustained so that the wedges tend to move downward and forward by gravity to the front of the magazine and against upturned shoulders h' on the supporting rails.

Beneath the wedges a' there is a vertically swinging finger h^2 carried by a rock-shaft h^3 . The lower end of the foremost wedge rests against a stop shoulder h^4 directly over the upturned end of the finger h^2 , so that when the finger rises, it lifts the wedge until the ears on the upper end of the same are above the stop-shoulder h' , whereupon the spacer, urged forward by those behind it, passes over the shoulder, and being thus released, descends by gravity through the channel h^5 to the end of the composed line in front of the star-wheel.

The shaft h^3 has a crank-arm h^6 connected by a link h^7 to an angular lever h^8 pivoted to the frame and carrying at the lower end the roller h^9 in the path of the short wedges a . A spring h^{10} , acting on the lever h^8 , urges the roller forward, as shown in Fig. 5. This roller is constantly rotated by means of a belt h^{10} passing downward to a roller h^{11} , or it may be driven by any other suitable means.

As each of the wedges or members a in its course toward the line, reaches the roller h^9 , as shown in Figs. 1 and 4, it is pulled downward by the latter, as shown in Fig. 5, so that the roller, riding upon the side face of the wedge, will be forced backward thereby. This retreat of the roller actuates the lever h^8 , which in turn, through the intermediate parts, lifts the finger h^2 and releases one of the long members a' . Thus it is that each of the short wedges, on approaching the line, causes at the proper time the positive delivery of the companion wedge a' . It will be understood that the essence of my invention in this regard lies in the employment of one of the wedge-shaped members to control or effect the delivery of its companion, and it will be manifest to the skilled mechanic that the details of the mechanism may be widely

modified without changing the principle of action, or passing beyond the scope of my invention.

In order to permit of more convenient arrangement of the other parts, and to prevent interference with the descending matrices, the magazine H for the spacer members a' , is arranged somewhat forward of the race-plate E , as shown in Fig. 3. In order to insure the proper and speedy delivery of the descending members a' into the line, an inclined shoulder or guide h^{14} is located in the path of said members immediately below the level at which they are suspended, so that as each of the members a' passes downward, its lower end is deflected edgewise, as shown in Fig. 7, in such manner that it will pass properly in front of the star-wheel and to its place at the end of the line.

In order to relieve the ears of the members a' from undue shock as they descend to their places in the line, I prefer to provide the fixed horizontal shelf h^{15} , as shown in Figs. 1, 2, 3 and 8, in such position that each of the members a' , descending into the line, will be arrested with its lower end upon this shelf before the ears at the upper end reach the sustaining rails. As the composition of the line progresses and the elongated line is crowded forward by the star-wheel, the members a' are carried forward with the line, until they pass one after another off from the end of the shelf, whereupon they settle gently to their final positions in the line, as shown in the drawings.

For the purpose of confining the matrices in close order as composition progresses, I provide the finger resistant I , carried on the end of a horizontally sliding rotatable rod i seated in guides in the frame and acted upon by a friction device of any suitable character, such for example, as that shown in Fig. 14, consisting of a friction pad or plate i^2 urged downward upon a rod by a spring i^3 contained in a casing or support i^4 .

As composition progresses, the finger will yield before the elongating line, and after composition is completed and delivery to the left is effected, the finger may be turned out of its operative position by rotating the rod i , after which the finger may be returned to its original position near the star-wheel preparatory to the composition of the next line.

When composition is carried on with great rapidity, it sometimes happens that the matrix or the spacer member will encounter the star-wheel immediately behind one of its points or arms in such manner that there is a slight hesitation in passing forward to the line. To overcome this difficulty I mount the star-wheel G on its spindle or shaft g in such manner as to allow a limited amount of lost motion between them. Any suitable coupling devices may be employed to this end, but I recommend the employment of

one or more studs g' on the shaft in position to encounter corresponding studs g^2 on the rear side of the star-wheel. The studs g' serve to turn the star-wheel forward in a positive manner, but if it so happens that a matrix encounters the star-wheel, as shown in Fig. 15, the wheel is permitted to turn forward in advance of the shaft to a limited extent, thus permitting the matrix to pass downward and forward without retardation. The shaft continuing its rotation, follows the star-wheel and immediately drives it again, the matrix in the meantime having assumed a favorable position, so that it is carried by the wheel properly to the line.

As the matrices and spacers join the line, they are retained in position, as shown in Fig. 10, by the laterally yielding spring-actuated dogs or pawls J , which in various forms are well known in the art.

For the purpose of delivering the composed line to the left from the assembling position to the devices which transfer it to the mold, I employ the horizontal slide K mounted in the frame and provided at the forward end with upturned lips which stand normally on opposite sides of the star-wheel and in advance of the line, so that when the slide is moved forward toward the position shown in full lines on the left hand of Fig. 1, it will carry the line of matrices before it along and between the supporting rails C and C' .

While the mechanism for delivering one spacing member to the line by means of the other or companion member is invented more especially for the purpose of delivering spacers, it is obvious that it may also be used for delivering matrices, so that when one letter matrix or fixed space is delivered toward the line, it will automatically cause the entrance of a second matrix or space by its side.

I believe the present to be the first composing mechanism in which a member, to become a part of the composed line, serves during its passage to the line, to cause the delivery of a second or companion member to the line.

General operation.—The operation of my mechanism is as follows:

The letter matrices and fixed spaces and spacer members a will be carried in the magazine and released therefrom one at a time in the manner in which matrices are ordinarily released from this class of machines.

Descending one at a time through the channels in the face-plate E , the matrices will be received upon the belt F and delivered thereby in front of the star-wheel G and into the assembling space between the rails or supports C and C' .

When a word is composed and the presence of a spacer or justifier is required, the member a is released from the magazine in the same manner as the matrices, and passes downward through the channels e' toward

the line. As it passes downward, it encounters the wheel h^9 and is carried thereunder and permitted to continue its course. As it passes beneath the wheel, it causes the latter to move backward toward the left, thereby operating the lever h^8 , and through the intermediate connections, the finger h^2 , which releases the foremost of the spacer members a' , which immediately descends into the line alongside of its companion a . The composition of the line then continues, another spacer is introduced, and so on repeatedly.

Having described my invention, I claim and desire to secure by Letters Patent:—

1. In a composing mechanism, expansible spacers consisting each of two unconnected wedges, in combination with means for directing one wedge to the line, and means controlled by said wedge to effect the delivery of its companion to the line.

2. In a composing mechanism, the combination of matrices, means for delivering them to the line, a series of short wedges and means for delivering them to the line, a series of long wedges and mechanism for delivering the long wedges to the line, said mechanism dependent for its action on the passage of the short wedges toward the line; whereby the delivery of one wedge is caused to insure the delivery of its companion.

3. In a composing mechanism, means for delivering members to the composed line, said means arranged to be actuated by other members in their passage to the line.

4. In a composing mechanism, the combination of the long wedges, their magazine, and means for delivering them singly from the magazine, said means adapted to be actuated by the passage of shorter wedges, substantially as described.

5. In a composing mechanism, a spacer magazine provided with means for releasing the spacer wedges therefrom one at a time, in combination with a power-driven roller movable bodily, and connections from said roller; whereby the passage of one spacing wedge is adapted to effect the release of the complementary wedge.

6. In a composing mechanism, in combination with a spacer magazine H , means for delivering spacers therefrom, a lever for actuating said means, a roller carried by the lever, and means for rotating said roller.

7. In a composing mechanism, in combination with a spacer magazine H and discharging finger h^2 , the lever h^8 connected with said finger, the roller carried by the lever, a spring tending to move the lever in one direction, and means for rotating the roller.

8. The combination of channeled guides C , C' , spacer members a of wedge-form, having at their upper ends ears seated in the guides and held thereby from rising, and spacer members a' of wedge-form, independently

supported at their upper ends on said guides and free to rise in relation to the guides and the members *a*, said wedges being unconnected, substantially as described.

5. 9. In a composing mechanism, the star-wheel, its driving shaft and intermediate connections; whereby the wheel is permitted a limited rotary motion on the shaft.

10. In a composing mechanism, a star-wheel and connections for rotating the same in a forward direction, said connections

adapted to permit an independent forward motion of the wheel; whereby it is permitted to turn ahead under the influence of the incoming matrices or spacers.

In testimony whereof I hereunto set my hand this twentieth day of June, 1907, in the presence of two attesting witnesses.

ALEXANDER DOW.
